UNITED STATES PATENT OFFICE.

BERNHARD DREYER, OF PHILADELPHIA, PENNSYLVANIA, ASSIGNOR TO
WILLIAM H. FRENCH, OF SAME PLACE.

DESIGN FOR CENTER-PIECE FOR CEILINGS.

Specification forming part of Design No. 6,712, dated June 24, 1873; application filed May 31, 1873.

To all whom it may concern:

Be it known that I, BERNHARD DREYER, of the city and county of Philadelphia, in the State of Pennsylvania, have invented and produced a new and original Design for a Center-Piece for Ceilings; and I do hereby declare the following to be a specification thereof.

The nature of my design is shown in the accompanying engraving, which forms a part of this specification, and represents so much of a center-piece, made according to the said design, as is necessary to show my invention. The leading features of this design are as follows:

The honeysuckle A in the space between the circular molding B and oval C. The double honeysuckles D (whether in panels or not) disposed alternately with rosettes E. The flower F in the space between the oval molding G and the ogee molding H or curved molding I. The outer molding H I K, whose outline consists of ogees, straight lines, and circular or oval curves, arranged substantially as shown.

circular or oval curves, arranged substantially as shown.

The details of the ornamentation may be varied.

What I claim as my invention, and desire to secure by Letters Patent of the United States, is—

1. The honeysuckle A in the space between the circular molding B and oval C.

2. The double honeysuckles D (whether in panels or not) disposed alternately with rosettes E, as shown.

3. The flower F in the space between the oval molding G, and the ogee molding H, or curved molding I.

4. The outer molding H I K, whose outline consists of ogees, straight lines, and circular or oval curves, arranged substantially as shown.

5. The entire design, substantially as shown.

Witnesses: BERNHARD DREYER.
